E. H. HICKISS,

Threshing Mach.

Patented Apr. 8, 1816.

The Oliver Reel Thrasher
Letter patent.

The Plaintiff repled to in their letter Patent and making part of the same containing a description in the words of the said Oliver Reel Thrasher himself of his Threshing and Cleaning Machine.

The frame of this machine is composed of scuttling or slate work, the posts are 4 by 4 inches square and four feet long. The plates and girths are 2 $\frac{1}{2}$ by 4. The frame is 4 feet 6 inches high from the ground to the top of the plates, and 3 inches made within the posts. The plates are framed into the posts 8 inches below the top in front and project over the hinder and 18 inches to support the straw Box. The upper girths are placed 12 inches below the top of the plates on the sides; the end girths one inch below the side ones, to admit the floor of the straw Box. The lower and girths are framed into the posts 10 inches above the foot of the plates, and the lower side girths directly above them; directly under the middle side girths, 12 inches from the back posts is placed the lower or bed cylinder, and is confined in a box at each end for the judgment to turn in. The upper cylinder in the same direction or purpose of the Box and exactly over the first bearing in boxes cut thro' the sides of the straw Box. This cylinder is made to receive sink and procure a proper bearing or pressure according to the quantity of straw spread in the box by springs placed over the judgment and made fast at one end to the underside of the plates. On one end of both cylinders outside of the straw Box, are fixed iron cogwheels containing 10 spikes 10 $\frac{1}{2}$ each two inches in length out of the rim of the wheel, which are 14 inches diameter. Each cylinder within the straw Box is 6 inches diameter. The upper cylinder is put in motion by the under one, and this by the operation of a wooden wheel 2 feet in diameter confined on the judgment outside of the before mentioned iron wheel. over the wooden wheel a band is passed, and crosses itself in its passage to the neck or barrel of the main shaft which gives motion to the threshing hammer. The neck or barrel of the said shaft between the frame and balance wheel is flattened down to 3 $\frac{1}{2}$ inches to receive the band. This shaft or barrel

is 4 feet long and 6 inches in diameter, has the positive movement at the fore end of the machine, in the centre of the shaft and away from the planes, an inserted 3 sets of Hammers of 3 blades in a set, placed at proper distances to operate upon the hafes of the hammers when motion is similar to a blacksmiths trip Hammer. On the further end of the shaft is fixed a balance wheel 40 inches in diameter constructed with four arms and felloes, 6 inches thick and 8 wide. The outer surface is divided & plated to receive two bands, one convex larger than the other & on the outside gives the first motion, and is adapted to either horse or water power. The lever or inside wood receives a band passing over it to a wheel about 3 inches in diameter on the end of the fanning mill shaft, the box extends $2\frac{1}{2}$ feet beyond the hind end of the frame over the fanning mill, which is constructed like a common dutch windmowing mill. Directly in front of the 3 cylinders is placed three wooden hammers or mallets of an exact thickness and just sufficient to fill up the straw box $1\frac{1}{2}$ inches wide and 17 inches long with hafes or handles $\frac{3}{4}$ feet long, the hafes are hung at 10 inches from the fore end upon a judgment to receive the Hams which give them motion like the trip Hammer.

Directly in front of the Hammer is a riddle screen or sieve made of sheet iron, over which the straw passes after the operation of the hammers and through which the grain is sifted into the fanning mill a quick motion is given to the screen or sieve up and down by means of a lever hung on a point near the centre thereof, and this lever obtains its motion from the operation of 12 small dogs inserted in the further end of the barrel shaft & inside of the straw box. Over each hammer is fixed a check spring like a Habit to a foyers Hammer. It is not considered necessary to describe that part of the machine which comprises the fanning mill, those mills being so commonly in use thro' our country that almost all persons must have a knowledge of them.
